UNITED STATES PATENT OFFICE.

JULIA J. LEIGHTY, OF GEDDES, SOUTH DAKOTA.

FOLDING CABINET.

1,133,866.

Specification of Letters Patent. Patented Mar. 30, 1915.

Application filed October 4, 1913. Serial No. 793,301.

To all whom it may concern:

Be it known that I, JULIA J. LEIGHTY, a citizen of the United States, residing at Geddes, in the county of Charles Mix and State of South Dakota, have invented certain new and useful Improvements in Folding Cabinets; and I do hereby declare the following to be a full, clear, and exact description of the invention, such as will enable others skilled in the art to which it appertains to make and use the same.

This invention relates to folding cabinets, and more particularly to that class known as bath cabinets.

One of the principal objects of my invention is to provide a folding cabinet adapted to receive a baby's wash tub, and provided with shelves and hooks for receiving the baby's clothing, sides of the cabinet adapted to swing outwardly so that when the cabinet is placed near a source of heat the sides will catch the heat.

Another object of my invention is to provide a folding cabinet of the class described which when not in use may be closed and will form an attractive article of furniture.

Another object is to provide a cabinet of the class described which will be simple, durable, and compactly arranged and which will be inexpensive to manufacture.

With these and other objects in view, the invention consists in the construction, combination and arrangement of parts herein-after more fully described and claimed, and illustrated in the accompanying drawing in which like characters of reference indicate like parts throughout several figures in which,

Figure 1 represents a perspective view of the cabinet in a closed position; Fig. 2 represents a perspective view of the same in an open position.

Referring more particularly to the drawing the base 5 is preferably rectangular in formation and is provided with casters 6. The back 7, is secured in any desirable manner to base 5, and said back is provided with a lower shelf 8, supported by braces 9, the shelf extending the substantial width of back 7, and is spaced above base 5. Shelf

8 is designed for the reception of a baby's bath tub and is provided centrally with an opening 10 adapted to receive a lug on the bottom of the tub (not shown) for preventing accidental removal of the tub from the shelf. An upper shelf 11 which is considerably smaller than shelf 8, is secured to

back 7, above said shelf and is intended to receive soap and other toilet accessories. The towel rack 12, is secured to back 7 above shelf 11 and the upper end of the back is provided on its front face with a looking glass 13. A pair of combined side and front walls are hinged to opposite edges of the back as illustrated at 14 and each combined side and front wall 15, and 16, respectively, is provided with a top 17, hinged as at 18, to the side wall and said top is adapted to fold outwardly when the cabinet is opened. The side and front walls are secured at right angles to each other and when in folded position each one of the pair incloses a half of the cabinet; that is, when in closed position the meeting line of the front walls will fall in the vertical transverse central plane of the cabinet as will also the meeting line of the folding top 17.

One of the side walls 15 is provided with a plurality of shelves 19 for receiving clothing or other articles and the opposite wall is provided with a plurality of hooks. It will be noticed that the shelves 19 are so positioned that when the cabinet is closed they will be between shelf 11 and rack 12. This is true also of hooks 20.

The sides are so hinged that the bottom edges thereof rest on the upper face of the base 5; when in closed position, and the side edges thereof rest against back 7 and the various shelves, hooks and towel rack will be hidden from view. The tops are hinged so that when in closed position they rest on the upper edges of the side and front walls. A door knob 21, is provided whereby the cabinet may be held in closed position.

In use the cabinet is intended to be rolled near a source of heat such as a stove and when in this position it may be opened whereby the front and side portions will catch the heat and retain the same in the cabinet and will effectually protect the baby from drafts.

It is evident from the foregoing that I have provided a very handy and useful cabinet for mothers in the care of their infants and which when in a folded position will present a very attractive and slightly article of furniture.

Although I have described the preferred embodiment of my invention I may desire to make such changes in the construction,

combination and arrangement of parts as do not depart from the spirit of the invention and scope of the appended claim.

Having thus fully described my invention what I claim as new and desire to secure by Letters Patent is:

An extendible cabinet comprising; a base, a back vertically mounted upon said base, two oppositely disposed side members 10 hinged to each edge of said back having two rigidly connected portions disposed at right-angles to each other, said sides combining to act as a support for a cover member and simultaneously as front and side

walls when closed, or simultaneously as an 15 extended portion of the back, lying flush with the same, and as parallel extended side walls when in open position, and a cover member hinged to and supported by each of said side members.

In testimony whereof I have signed my name to this specification in the presence of 20 two subscribing witnesses.

JULIA J. LEIGHTY.
